[57] CLAIM

The ornamental design for a scuba tank dolly float, as shown and described.

DESCRIPTION

FIG. 1 is a perspective view of a scuba tank dolly float embodying my new design, with a scuba tank attached thereto;

FIG. 2 is a perspective view of the scuba tank dolly float illustrated in FIG. 1 floating in water without the scuba tank attached thereto;

FIG. 3 is a front view thereof;

FIG. 4 is a side view thereof;

FIG. 5 is a rear view thereof;

FIG. 6 is a top view thereof; and,

FIG. 7 is a bottom view thereof.

The broken line showings of a scuba tank and straps in FIG. 1, and a flag in FIG. 2, are for illustrative purposes only and form no part of the claimed design.
